United States Patent Office.

JOSEPH FANYOU, OF BRIDGEPORT, CONNECTICUT.

Letters Patent No. 65,734, dated June 11, 1867.

IMPROVEMENT IN LUBRICATORS.

The Schedule referred to in these Letters Patent and making part of the same.

TO ALL WHOM IT MAY CONCERN:

Be it known that I, JOSEPH FANYOU, of Bridgeport, in the county of Fairfield, and State of Connecticut, have invented a new and useful Improvement in Lubricators or oil-cups; of which the following is a full, clear, and exact description, reference being had to the accompanying drawing, which makes part of this specification, and which represents a vertical central section through my improved lubricator.

My invention has for its object the production of a cheap, simple, and effective lubricator.

To carry out this object, I cast a cup, A, of brass, of the form shown in the drawing, open at top and bottom, and having a transverse bar, B, near its bottom. A screw-cap, C, with a milled edge, closes the top of the cup, while a tubular-screwed spindle, D, screws into the bottom far enough to abut against a plug, b, or the bar B, and thus close the channel d. The lower part E of the spindle is also provided with a male screw, e, so that it may be screwed into its support, into which a shoulder, F, limits the extent of its insertion. A packing-ring i is inserted between the bottom of the cup and the top of a milled nut, I, in order to prevent leakage at that point. When in the position shown in the drawing, the plug b closes the channel d, and prevents the flow of the oil.

The operation of the oiler is as follows: The screw-cap is removed and the cup filled with oil; the cup is then replaced. By turning the cup on its spindle, the top of spindle D is separated from the plug b, and the oil flows through the channel to the point to be lubricated. By screwing the nut I up or down the distance to which the spindle enters the cup, and consequently the area of the opening between the plug and its top, can be regulated, and this regulates the flow of oil.

My lubricator is easily attached to or removed from its support, and from its simplicity is especially adapted to parts in rapid motion.

I claim the combination, as described, of the cup and the transverse bar with the screwed spindle and regulating nut.

In testimony whereof I have hereunto subscribed my name.

JOSEPH FANYOU.
